A safety overcap for an easy opening container having an end closure with a tear portion defined by a score line and a pull tab secured to the tear portion by an integral rivet. The overcap includes a panel and a peripheral flange adapted to be detachably snap fitted over the seam of the container. The overcap is formed with a slot having co-acting pull tab for removing the tear strip and a position permitting tilting of the pull tab.

SAFETY OVERCAP FOR EASY OPENING CONTAINER

BACKGROUND AND SUMMARY OF THE INVENTION

The present invention relates to easy opening containers of the type having an end panel provided with a tear strip defined by a score line. The tear strip is removed by a pull tab which is attached thereto and is operative to separate the tear strip from the end panel to form a pour opening.

The present invention is particularly concerned with a means for preventing the inadvertent or accidental opening of the container so that the contents may not be accidentally consumed. This is a problem when the contents of the container are of the toxic or poisonous type and a child has access thereto. Under these conditions, the child may open the easy opening container and become seriously ill. The present invention is concerned with the provision of an overcap which requires manipulation before the pull tab can be tilted to a position for opening the container.

The overcap of the present invention comprises generally a cover panel having a peripheral flange which is adapted to detachably snap fit and be turnably mounted on the double seam formed by double seaming the end closure to the container. The cover panel includes means operative in one position for precluding access to the pull tab thereby to prevent tilting of the latter into a position for opening the container. In one form of the invention, the cover panel is provided with a slot covered by a hinged flap overlying the tear portion and pull tab. In another form, the cover panel is provided with a slot and the overcap is rotatably mounted so that in one angular position, the pull tab underlies the cover panel and in a second angular position wherein the tab lies in the slot so as to be capable of being tilted to a position for removing the tear portion.

BRIEF DESCRIPTION OF THE DRAWINGS

FIG. 1 is a top plan view of an easy opening container showing a safety overcap incorporating the structure of the present invention and positioned to prevent manipulation of the pull tab for opening the container.

FIG. 2 is a top plan view similar to FIG. 1 but showing the overcap in a position wherein the tab is capable of being manipulated for removing the tear strip.

FIG. 3 is a cross-sectional view taken generally along the lines 3-3 of FIG. 1.

FIG. 4 is a top plan view of a container showing another embodiment of safety closure with the safety closure shown in a position preventing manipulation of the pull tab so that the tear portion may not be removed.

FIG. 5 is a top plan view similar to FIG. 4 but showing the overcap in a position for removing the tear portion.

FIG. 6 is a cross-sectional view taken generally along the lines 6-6 of FIG. 4.

FIG. 7 is a cross-sectional view taken generally along the lines 7-7 of FIG. 5.

FIG. 8 is a top plan view of an easy opening container of a further embodiment of safety overcap with the overcap shown in a position wherein the pull tab is held

restrained against the end closure so that the tear strip may not be opened.

FIG. 9 is a top plan view similar to FIG. 8 but showing the flap removed to make the pull tab accessible so that the tear strip may be removed.

FIG. 10 is a cross-sectional view taken generally along the lines 10-10 of FIG. 8.

FIG. 11 is a cross-sectional view taken through the longitudinal center of the container and safety overcap mounted thereon and showing the position of the flap prior to being removed from the overcap.

BRIEF DESCRIPTION OF THE PREFERRED EMBODIMENT

15 Referring now to the embodiment of the invention disclosed in FIGS. 1 to 3 there is shown an easy opening container 10 comprising generally a container body 11 to which an end closure 12 is attached by means of a double seam 13.

20 Detachably secured to the double seam or rim 13 is an overcap 14 made from plastic or the like. The overcap 14 includes a central cover panel portion 16 and a peripheral groove 17 defined by a downwardly depending flange 18. The flange 18 may have an inwardly projecting lip 19 underlying the double seam 13. The flange 18 and lip 19 are resilient so as to snap fit over the double seam 13 and thereby maintain the overcap detachably fastened to the container 10. At the same time, the overcap 14 is also rotatable on the end closure 12.

25 The end closure 12 includes an end panel 20 provided with an easy opening structure in the form of a score line 21 defining a substantially tear drop shape tear portion or strip 22. Fixed to the narrow end of the tear portion 22 by an integral rivet 23 is a pull tab 24. The pull tab 24 is of substantially standard construction including a finger grip 26 and a pair of fulcrum legs 27-27 about which the pull tab 24 is tilted to separate the tear portion 22 from the end panel 20 of the end closure 12. In the embodiment shown, the end panel 20 is provided with a plurality of angularly spaced detents 29 seatably within complementary angularly spaced depressions 30 formed on the underside of the cover panel 16.

30 The cover panel 16 is provided with a substantially rectangular slot 32 extending diametrically across the overcap. The slot 32 is sufficiently wide to accommodate the tear strip 22 and a pull tab 24 therein so that the pull tab may be tilted upwardly about the fulcrum legs 27-27 to separate the tear strip 22 from the end panel 20 when it is desired to open the container.

35 The underside of the cover panel 16 is provided with an arcuate recess 33 which is adapted to overlie the finger grip 26 of the pull tab 24 as shown for example in FIGS. 1 and 3. At least a portion of the finger grip 26 of the pull tab 24 is accommodated within the recess 33 when the overcap 14 is rotated and the slot 32 is located substantially normal to the tear strip 22 and pull tab 24 as shown in FIG. 1. The overcap 14 is restrained in this position by the spaced detents 29 seated in the complementary spaced depressions 30. In FIG. 1 as described above, the pull tab 24 is partially received within the recess 33 so that access thereto for tilting the latter is not possible. When it is desired to open the container 10, the overcap 14 is rotated to the position shown in FIG. 2 wherein the slot 32 is axially aligned with the tear portion 22 and the pull tab 24 so that ac-

cess may be had thereto for tilting the pull tab 24 and removing the tear strip 22 in the normal manner.

Turning now to FIGS. 4-7, there is shown attached to a container 10 another embodiment of overcap 114 for precluding inadvertant opening of the container. The overcap 114 comprises a cover panel 116 from which there depends a peripheral flange 118 and an end lip 119. The flange 118 and lip 119 define a recess 117 which snap fits over the double seam 13 of the container 10. The cover panel 116 is formed with a pair of diametrically spaced projections 121 which seat within depressions 122 formed in the container end panel 20.

The overcap cover panel 116 is formed with a slot 132 which accommodates the tear portion 22 and the pull tab 24 when the overcap is turned so that the slot 132 is aligned with the tear portion 22 and pull tab as shown in FIG. 5. In the normal non-use position, the pull tab 24 is turned about the rivet 23 to a position generally normal to the longitudinal axis of the tear portion 22. The pull tab 24 is restrained in this position by a detent 130 which engages one side of the tab 24.

The end of the pull tab 24 is accommodated within a recess 133 formed on the underside of the cover panel 116. The recess prevents access to the pull tab for tilting the latter into a position for opening or removing the tear strip 22.

To open the container, the edge of the pull tab 24 adjacent the detent 130 is lifted slightly so as to clear the latter. The overcap 114 is thereafter rotated counter-clockwise in the direction of the arrow as shown in FIGS. 4 and 5. The pull tab 24 seated within the recess is caused to turn about the rivet 23 to the position shown in FIG. 5 in alignment with the tear portion 22. Thereafter, the overcap 114 is rotated clockwise to its original position shown in FIG. 4. The pull tab 24 is now in a position for lifting or tilting so that it may be rocked about its fulcrum legs 27-27 to open the container by severing the score line 21 and separating the tear strip 22 from the end panel 20.

Referring now to FIGS. 8 to 11 there is shown still another embodiment of a safety overcap arrangement. The safety overcap arrangement 214 comprises generally a cover panel 216 having an outer peripheral flange 218 terminating in an inwardly projecting lip 219. The flange 218 and lip 219 define a slot 217 which accommodates the double seam 13 therein when the overcap 214 is snap fitted thereon.

The cover panel 216 is provided with a pair of narrow slits 231-231 terminating adjacent the flange 218

along one side thereof and extending downwardly for the full length of the flange 219 on the other side. The slits 231-231 form a flap 232 which may be of lesser thickness than the remainder of the cover panel 216 and is hinged about a reduced section 233 as shown. The flap 232 is sufficiently thin to accommodate the thickness of the pull tab 24 when it lies flush with the remainder of the upper surface of the cover panel 216.

Projecting from the outer end of the flap 232 is a downwardly depending finger grip tab 234. Spaced inwardly from the finger grip tab 234 is a second flange 236 which co-acts with the tab 234 to releasably embrace the double seam 13. Removal of the flap 232 by tearing along the reduced section 233 provides a slot 237 through which the tear portion 22 and pull tab 24 are accessible. After removal or lifting of the flap 232, the tab 24 may be tilted upwardly so as to remove the tear portion 22 from the end panel 20.

What is claimed is:

1. A safety overcap for an easy opening container having a tear strip defined by a score line and a pull tab secured by an integral rivet to the tear strip for removing the same, said safety overcap comprising a cover panel and a peripheral flange adapted to snap fit over the end seam of the container, said cover panel having a slot through which said pull tab is accessible for tilting movement, and means coacting with said slot movable between a position rendering said pull tab inaccessible for separating said tear strip from said container and a position rendering said pull tab accessible whereby said pull tab may be tilted for separating said tear strip from said container.

2. The invention as defined in claim 1 wherein said means comprises a flap hingedly secured to said panel and movable between a position above said panel and a position co-extensive with said panel.

3. The invention as defined in claim 2 wherein said flap is removable from said overcap.

4. The invention as defined in claim 1 wherein said overcap is turnable on said end seam, said panel includes a recess on the underside thereof communicating with said slot, said recess accommodating said pull tab therein in one angular position of said overcap so as to preclude tilting thereof and being clear of said pull tab in a second angular position of said overcap.

5. The invention as defined in claim 3 wherein said overcap includes detent means co-acting with means on the container for restraining free relative turning of said overcap.
